CORNER CAP FOR FURNITURE
 Joseph B. Pompa, West Los Angeles, Calif.
 (151 S. Westchester Drive, Anaheim, Calif.)
 Filed Dec. 18, 1961, Ser. No. 160,133
 4 Claims. (Cl. 45—68.4)

This invention relates to an improved and structurally unique corner cap for furniture corners which, if sharp, as is often the case, present ever present danger to persons who accidentally come into collision therewith, said cap constituting a protective guard and greatly lessening the likelihood of serious injury, particularly wherein small children are involved.

Stated otherwise the invention pertains to a safeguarding or safety cap or pad which is desirable for intended purposes in that it embodies cushioning properties and is therefore capable of achieving the end result desired.

In carrying out the invention a simple, practical and economical adaptation is employed. To this end the cap is made of moldable plastic material, for example polyvinyl plastics. The finished product is triple-walled, having a top wall to reside in contact with the table or other furniture top and having depending vertical walls to bridge the corner's sharp edge and to attach themselves to the adjacent rim or equivalent surfaces.

The invention further relies for novelty on a one-piece molded cap which may be (1) transparent (2) colored to correspond with the color of the job at hand or (3) made opaque and finished to represent a metal cap, whereby to thus offer protection and to enhance the appearance that it will be pleasing to the eye of the observer.

Then, too, the interior surfaces of the three component walls are flat and coated with pressure responsive adhesive material whereby to permit ready application and removal of the cap.

These together with other objects and advantages which will become subsequently apparent reside in the details of construction and operation as more fully hereinafter described and claimed, reference being had to the accompanying drawing forming a part hereof, wherein like numerals refer to like parts throughout, and in which:

FIGURE 1 is a view in perspective showing a coffee table, this being the example of one article of furniture herein under consideration, said table being provided on the four corners thereof with the improved safety cap;

FIGURE 2 is a top plan view on an enlarged scale showing one corner portion of the table and how the cap is applied and appears in top plan;

FIGURE 3 is a section on the line 3—3 of FIGURE 2, looking in the direction of the arrows; and

FIGURE 4 is a perspective view of the cap by itself.

As above implied the word "furniture" is used to cover the various articles herein under consideration. The typical table shown in FIGURE 1 will suffice to illustrate the principal purpose of the invention; namely, covering what may be called the dangerous point 6 at the top of the vertical corner edge 8. The invention comprising a small cap is not intended to cover the entire edge 8 or to extend any appreciable extent to the left or right thereof. The top surface of the table top 10, described as the horizontal surface is denoted at 12. The marginal skirt or rim of the table is denoted at 14.

The novel safety cap depicted in the views of the drawing is denoted as an entity by the numeral 16. It is small, relatively speaking, is of one-piece, moldable plastic construction. It is preferably made from compressibly resilient relatively soft polyvinyl plastic material and may be either transparent or opaque. The top wall is denoted at 18 and shown in FIGURE 3 is tapered and terminates in a feather edge 20. The marginal edges 22 of the de-

2

pending walls are also gradually reduced in thickness or tapered to provide feather edges 22. One depending wall is denoted at 24 and the other one at 26. The interior surfaces of the walls are substantially flat and are coated with a transparent pressure sensitive adhesive material 28 similar to that employed on various types of adhesive tapes. The exterior surfaces are substantially convex as brought out conveniently at the point 30 in FIG. 3. The several walls are of triangulate shape in elevation. Thus it will be seen that the cap is a guard and also a cushion, its purpose, as suggested, being to minimize the likelihood of injury to any persons who by accident should collide with or fall against an otherwise unprotected sharp pointed corner. Such corners are usually present on coffee tables, end tables, card tables, sink tops, cabinets, etc. While the invention was expressly designed to accord protection to small children it is obviously a source of protection to any person who might encounter the misfortune of a slip and fall adjacent to the table or similar corner. The cap is provided with transparent mucilage and is therefore self-retaining. Consequently it can be pressed on or pulled off with ease. When a transparent plastic material is used the cap is hardly noticeable and allows the shade or finish of the furniture to be seen through the walls of the cap. When using a plastic material with a properly shaded color incorporated therein the cap actually contributes to the ornate appearance of the corner which is covered thereby. Using opaque metallic covered caps actually enhances the appearance of the piece of furniture so that the cap becomes not only a safeguard but an ornament.

Since it is known that permanent rigid corner caps are used and made of aluminum and some are highly polished and chromium plated and perhaps brass these types of caps are not readily applicable and removable as is the herein disclosed cap. This is to say the caps can be sold in packages with instructions for use. Therefore, it is believed that the instant invention, simple and practical as it is, nevertheless constitutes a significant advance in the art of safety caps.

It is believed that a careful consideration of the specification in conjunction with the views of the drawing will enable the reader to obtain a clear and comprehensive understanding of the construction, features and advantages of the unique cap. Therefore, a more extended description is believed to be unnecessary.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

55. What is claimed as new is as follows:

1. For use on a sharp corner on a piece of furniture such as, for example, an end table, coffee table, metal cabinets and the like; an accident forestalling and preventing cap which is applicable to and designed and adapted to safely cover the dangerous components of a corner of said table, said cap being made from moldable compressibility resilient material, being possessed of prerequisite shock absorbing and cushioning properties capable of safeguarding children, adults too, who might accidentally or otherwise forcibly collide with the aforementioned corner, said cap being of one-piece construction and embodying a top wall having an interior flat surface adapted to superimpose itself upon and conformingly overlie an intended minimal surface portion of the furniture's top in proximity to said corner, and a pair of depending complementary walls having contiguous edges thereof adjoined to each other and additional contiguous edges adjoined

with coinciding marginal edges of said top wall, also having flat uninterrupted attaching and retaining surfaces designed and adapted to conformably contact the furniture surfaces to the left and right of the usual sharp vertical edge portion of said corner, the entire attachable portions of the flat surfaces having flatwise contact with the cooperating furniture surfaces and being coated with pressure-responsive adhesive media, said cap being limited in its makeup to three walls which are complementary to each other and substantially identical in construction and are generally triangulate in plan and are each provided with a convex exterior rounded surface.

2. The structure according to claim 1, and wherein said cap is made from transparent plastic material.

3. The structure according to claim 1 and wherein said cap is molded from plastic material (polyvinyl) and col-

ored to match the color of the particular surface to which it is attached.

4. The structure according to claim 1, and wherein said cap is molded from opaque plastic material expressly made to imitate metallic caps such as are currently employed for rounding, reinforcing and ornamenting furniture corners.
